UNITED STATES PATENT OFFICE.

ORRIS H. WARREN, OF BALDWINSVILLE, NEW YORK.

IMPROVEMENT IN OIL-CANS.

Specification forming part of Letters Patent No. **143,107**, dated September 23, 1873; application filed August 16, 1873.

To all whom it may concern:

Be it known that I, ORRIS H. WARREN, of Baldwinsville, in the county of Onondaga and State of New York, have invented a new and Improved Oiler, of which the following is a specification:

The accompanying drawing represents a vertical central section of my improved oiler for elevated parts of machinery.

The object of my invention is to construct a convenient oiling device for the purpose of supplying shafting, bearings, and other parts of machinery, which are elevated to be out of reach, with the necessary oil, without the use of steps or ladder. The oiler is simple and effective, and allows an easier and quicker oiling than the inconvenient methods hitherto in use. My invention consists mainly of a tubular rod, of suitable length, in which is an oil-receiving chamber, and to which is secured a hollow handle, in which the air-chamber is arranged. From the oil and air chambers the oil is forced out through the discharge-pipe at the end of rod by means of a pump arrangement operated by the thumb. Projecting lugs or ears at the end of discharge-pipe raise the covers of boxes or cups over bearings.

In the drawing, A represents the tubular rod, of suitable dimensions and material, which is gradually tapering off to the upper curved end of the discharge-pipe B, which extends centrally through the full length of rod A. The handle C is attached to the lower end of rod A, being also hollow, and of the same material as the rod. In the lower and wider part of rod A is arranged the oil-receiving chamber D, which is filled by means of an orifice, a, closed by screw-cap a', and which communicates, by vent-holes b¹ in top partition b and b² at end of rod, with the outer air. A stop-cock or faucet, d, passes through the oil-receiving chamber D into discharge-pipe B, and serves for the purpose of letting the oil back from the upper part of the discharge-pipe into the oil-chamber D. The air-chamber C', formed within the handle C, connects by a tube, e, with the oil-chamber D, which tube extends to the bottom of air-chamber, opening thereby means of a valve, e'. The discharge-pipe B passes also down to the bottom of the air-chamber

C', and is provided there with a valve, f, which is formed by widening the discharge-pipe B into a chamber, g, having a narrower end tube, f¹, which guides a smaller tube, f², sliding therein. The tube f² closes tube f¹, by means of its conically-projecting cap g¹ at the top, and has an orifice, g², near its lower end. When the valve f is brought into action the tube f² rises till orifice g² is above the guide-tube f¹, when the oil will pass into the wider chamber g, and thence up into discharge-pipe B. A projecting lug, h, of chamber g arrests the upward motion of inner tube f², preventing thereby its disconnection from tube f¹, and securing the regular flow of oil. The upper end of the discharge-pipe B is bent first into the shape of a large U, and again, at the extreme end, in the shape of a small inverted U, as shown in the drawing. The object of the curved end part is to prevent the dripping of the oil at the end of the discharge-pipe, the oil being drawn back by the closing of valve f. The ears l, near curved end of pipe B, serve to raise the covers of boxes or cups for oiling the bearings, shafts, &c. At the upper part of handle C is applied the air-bulb E, of rubber or other suitable material, which is connected through air-chamber C', by a small tube, i, with a small air-chamber, F, attached to handle C opposite bulb E. A second tube, i', opens from chamber F into air-chamber C'. The design of the air-chamber F and tubes i and i' is to prevent the oil from rising and flowing into the bulb E, protecting it thus from the action of the oil, and keeping the force-pump action of the bulb unimpaired. In whatever position the oiler may be held the air-chamber F will prevent the entering of oil into the bulb.

By holding the handle C and pressing with the thumb on the bulb E the oil is first drawn by the expansion of the bulb through tube e into the air-chamber C'. The repeated pressure on the bulb closes valve e, lifts valve f, and forces the oil up through the discharge-pipe to the machinery, while the receding of valve f, or the expansion of the bulb, draws the oil back from the end of the discharge-pipe without dripping.

By means of this simple force-pump action

of the oiler elevated parts of machinery may be easily oiled, without the least waste and loss of time.

Having thus described my invention, I claim as new and desire to secure by Letters Patent—

1. The oiler for elevated parts of machinery, consisting of tubular rod A with oil-receiving chamber D, handle C with air-chamber C', bulb E, and air-receptacle F, in combination with discharge-pipe B, all arranged and operated substantially as and for the purposes described.

2. The oil-receiving chamber D in combination with air-chamber C', tube e, valve e¹, and bulb E, to draw oil down from the oil-chamber into the chamber C' by the expansion of the bulb, as set forth.

3. The combination of valve f of discharge-pipe B with air-chamber C' and bulb E, to force oil through discharge-pipe to elevated machinery, as described.

4. The combination of bulb E, by tube i i', with air-chamber C' and F, to prevent access of oil to bulb, as specified.

5. The discharge-pipe B, having double U-shaped end with ears l, for the purpose set forth.

6. The valve f, consisting of outer guide-tube f¹ g, inner tube f² g¹ with orifice g², and stop h for securing regularity of action, as described.

ORRIS H. WARREN.
